UNITED STATES PATENT OFFICE

BERNARD J. JURON, OF CHICAGO, ILLINOIS

TRUSS CONSTRUCTION

Application filed August 16, 1928. Serial No. 300,029.

The present invention relates to improvement in structural units and more particularly to a novel truss structure, the main purpose of which being to provide a structural detail of this character, capable of being easily and cheaply manufactured, and which in use will be far more durable and possess considerably more strength than elements of this nature now employed.

10 The prime object of the invention resides in the peculiar slitting of a single piece of ductile metal and preferably of an I-beam shape in cross section in such a manner that when the longitudinal edge portions of the beam are separated, interconnecting diagonal braces will be provided and by interposing struts between the chords or edge portions of the beam, in a position secured to the adjacent ends of the said braces, a very stable 20 structure will result.

Another important object resides in a truss member constructed in the foregoing manner with the end in view of conserving material and obviously reducing the manufacturing 25 costs substantially.

Still another object of importance resides in the construction of a truss in the manner afore stated wherein the braces are provided in angularly disposed and opposed groups 30 while struts connect the upper and lower ends of the longitudinal edge portion, to sustain the truss in its expanded state.

Still another important object resides in the fact that in the completed truss structure no part thereof is directly contingent or dependent in any manner upon welds, rivets, solder or bolts for its load carrying capacity, except in so far as it is necessary to hold 40 the vertical brace members in their place by the use of welds, rivets, solder, bolts or interlocking joints, and other connections or any or either of them.

After reading the following specification 45 and claim, other important objects and ad-

vantages of the invention will become apparent.

In the drawings:

Figure 1 is a side elevation of the I-beam or similar shaped member or ductile metal, 50 slitted in the novel manner preparatory to the expansion thereof.

Figure 2 is a side elevation of the beam expanded to provide a truss structure.

Figure 3 is a side elevation of the constructed truss with the brace members interposed between the longitudinal edges thereof for sustaining the truss in its expanded position, and

Figure 4 is a fragmentary side elevation of 60 the improved truss in a somewhat modified form.

Referring to the drawings, wherein like numerals designate like parts, an elongated I beam 1 having the usual flanged longitudinal edges 2-2 is slitted in a peculiar manner throughout the major portion of its length in a manner whereby the flanged edge portions of the beam are spaced apart to constitute chords in a truss structure, such as is shown 70 clearly in Figure 2.

In slitting the beam preparatory to spreading the flanged edge portions apart, spaced transverse slots 4 are formed in the beam web, and an elongated slit 3 is formed longitudinally at an intermediate point and substantially parallel to the flanged edge portions 2-2, said slit 2 communicating with and extending longitudinally at opposite sides of the central slot 4.

Elongated slits 5-5 are formed in the web of the beam 1 in longitudinal spaced relation and in longitudinally alined respect to themselves and the slit 3, the slits 5 extending from corresponding ends of the slots 4 toward the ends of the beam. The slits 5 are formed in the beam outwardly of each end of the slit 3. A second group of slits 6-6 are formed in longitudinal spaced relation throughout the major length of the beam 1

and adjacent the opposite flanged edge of the beam.

The slits 6 communicate with all the transverse slots 4 excepting the central slots 4, and 5 are arranged in parallelism with the slits 5, excepting the end slits 5, and extend longitudinally inward from the opposite ends of the slots 4, with reference to the ends from which the slits 5 extend. The innermost slits 6 are 10 arranged in parallelism with the before mentioned slit 3.

Obviously, by spreading one flanged edge portion of the beam to a position spaced from its complementary flanged edge portion, a 15 structure such as is shown in Figure 2 of the drawings will be obtained. By this method of slitting and otherwise forming the beam 1 and separating the opposite edge portions to form chords in the manner shown, a novel 20 truss structure is obtained which includes an equal number of diagonal braces 8-8 arranged in diverged relation toward opposite ends of the structure.

In this expanded position, the respective 25 ends of the beam 1 serve as bearing extensions 9-9 while the slots 4 serve to provide lower and upper abutments or shoulders 9 α and 10 respectively.

As is clearly shown in Figure 3, a plurality of struts 11 are arranged between the opposite longitudinal edge portions or chords of the expanded structure shown in Figure 2, so that their end portions will rest alongside of and against the respective shoulders 9 α and 10. The struts may be thus 35 strongly secured to the structure by soldering, welding, interlocking joints or some similar method, or by any means found suitable. In this connection it will be observed 40 that each brace member 11 is arranged at right angles to the longitudinal edge portions and that each brace member 11 rests at one end of one abutment 9 α and at the opposite end of the abutment 10 below. 45 From this it follows that the abutments 9 α and 10 afford strong means for the connection of the brace members 11.

The bearing extensions 9-9 at the respective ends of the expanded structure may be 50 split inwardly and spaced in the manner shown in Figure 4. The portion of the lower flanged edge or chord indicated by dotted lines may be then removed while the lower edge portion of the upper flanged portion 55 may be provided with a bearing plate 12, whereby the structure shown in Figure 4 may be employed in certain types of building arrangements.

It will be apparent from the foregoing 60 that the production of my novel truss is attended by the separation of the flanges of a sheared beam in such a manner as to create two chords of a truss together with integral braces; also, that in my truss the bracing in 65 the expanded element forms a triangle at the

center of the element only, and the remainder of the outline consists of a series of parallelograms. It will also be apparent that in my improvement a completed structure is not attained until after the insertion of the struts 70 11, and that my improvement does not entail the employment of splices and is of such character that the original length of the finished products is the same as the unfinished 75 which is materially advantageous because it avoids waste of material.

It is to be understood that certain changes in the specific manner of carrying out the foregoing invention may be resorted to, without departing from the spirit of the invention or the scope of the appended claim.

Having thus described my invention, what I claim as new is:—

A truss element of ductile metal made from a shape such as an I beam, the web portion of said I beam having been slotted with two rows of interrupted longitudinal cuts and properly spaced transverse cuts connecting adjacent ends of the interrupted longitudinal cuts of the rows and in such a manner that when the two flange portions of said I beam have been separated and spaced in parallelism with one another, the intermediate web portion will have been stretched and become a series of brace members and the resultant outlined appearance will show the two central braces at the lower flange member and forming a triangle with the upper flange member and all other brace members into groups, one group of either side of a central triangle, the brace members in each group being spaced in parallelism with each other and with the nearest brace member of the central triangle, the transverse cut defining upper and lower abutment shoulders, and vertically disposed compression struts abutting against the opposite sides of adjacent shoulders.

In testimony whereof I affix my signature.

BERNARD J. JURON.
